(57) CLAIM

The ornamental design for a detachable computer light, as shown and described.

DESCRIPTION

FIG. 1 is a front perspective view of a detachable computer light showing my new design in a first configuration;

FIG. 2 is a rear perspective view thereof;

FIG. 3 is a right side view thereof, the left side being a mirror image thereof;

FIG. 4 is a rear perspective view thereof, shown attached to a laptop computer, said laptop computer not forming part of the invention;

FIG. 5 is a front view thereof in an alternate straight configuration;

FIG. 6 is a back view thereof;

FIG. 7 is a perspective view thereof in an alternate coiled configuration; and,

FIG. 8 is a perspective view thereof in an alternate "S" shaped configuration.

The broken lines shown in the drawings illustrate portions of the design and environmental structure, and form no part of the claimed design.
